(57) **CLAIM**

The ornamental design for a wide head hook rule, as shown and described.

DESCRIPTION

FIG. 1 is a front, top, left side isometric perspective view of a wide head hook rule in accordance with my design; FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines illustrate portions of the wide head hook rule which form no part of the claimed design.

The claimed design is shown with a symbolic break in its length. The appearance of any portion of the article between the break lines forms no part of the claimed design.
